JOSEPH ROSENBERG, OF NEW YORK, N. Y.

ADJUSTABLE SHOWER-BATH FIXTURE.

Specification of Letters Patent. Patented June 27, 1916.

1,188,681.

Application filed April 1, 1915. Serial No. 18,525.

To all whom it may concern:

Be it known that I, JOSEPH ROSENBERG, a citizen of the United States, and a resident of New York, county and State of New York, have invented a certain new and useful Improvement in Adjustable Shower-Bath Fixtures, of which the following is a full, clear, and exact specification.

This invention relates more particularly to a class of devices adapted to be used by persons for bathing purposes.

My invention has for its object primarily to provide a fixture designed to be utilized especially when a person is taking a bath whereby a sheet may be suspended so as to be disposed in a bath tub to confine the flow of the water into the tub as well as permitting the sheet to be neatly folded and swung clear of the tub when not in use, and which 20 is also of a form adapted to allow persons of various heights to conveniently take shower baths.

The invention consists essentially of a stationary support, or post projecting upwardly at preferably one side of the bath tub, and on this post is rotatably mounted a bracket from which the bath sheet is removably suspended. The bracket is of a foldable form, and when in its normal position for use the sheet may be disposed interiorly of the tub, and when not in use the parts of the bracket may be folded together for also folding the sheet so that both the bracket and the sheet may be swung clear 35 of the tub. Also on the post is mounted a substantially semi-circular hollow pipe-like water distributor having perforations in its inner periphery, and this distributor is adapted to be connected to the faucet of the 40 bath tub leading from the source of water supply whereby the bather may take a shower bath.

Other objects of the invention are to provide means for adjustably connecting the 45 water distributor to the post for permitting the distributor to be positioned at various elevations on the post whereby persons of different heights may conveniently take the shower as well as permitting the shower to 50 flow on the body of the bather without wetting the hair; and to provide a flexible tubular member for connecting the shower distributor to the water supply faucet.

A practical embodiment of the invention 55 is represented in the accompanying drawing forming a part of this specification in

which similar characters of reference indicate corresponding parts in all the views, the said invention being more fully described hereinafter, and then pointed out in 60 the claim at the end of the description.

In the drawing, Figure 1 is a side elevation, partly broken away, of a bath tub showing one form of device embodying my invention as used in conjunction therewith. 65 Fig. 2 is a top plan of the foldable bracket and the semi-circular adjustable shower member of the device, the supporting member thereof being shown in cross-section. Fig. 3 is a top plan of the bracket when 70 folded, and Fig. 4 is an enlarged sectional view of the parts of the device which serve as means for adjustably holding the shower member on the supporting post.

The device, or adjustable fixture has a support, or post 10 which is disposed upwardly from preferably the central part of one of the sides of a bath tub, as 11, having interiorly thereof a faucet, as 12, leading from a source 75 of water supply, and this post is suitably 80 held so as to be stationary. The post 10 may be of any desired height, and on this post at an elevation above the bath tub is rotatably mounted a foldable bracket, as 13, of preferably a triangular shape.

The bracket 13 has a split strap, or sleeve 14 which is disposed on the post 10, and the parts of the split sleeve are fastened together by screws or otherwise so as to be revolubly movable on the post. To two 90 spaced lugs on the front of the sleeve 14 are pivoted, at 15 and 16, one of the corresponding ends of two side arms 17 and 18 of the foldable bracket, and these arms are adapted to be swung to and from each other above 95 the bath tub transversely with respect to its open top. Both of the arms 17 and 18 are of lengths so that when swung in diverging directions, as shown in Figs. 1 and 2, their outer ends will correspond with vertical 100 lines equal with or slightly beyond the ends of the bath tub as well as extending on a vertical plane corresponding to the side edge of the tub which is farthest from the post 10. To the outer end of the side arm 17 of 105 the bracket is pivoted, at 19, one end of a third arm 20 extending transversely toward the arm 18, and to the outer end of the arm 18 is pivoted, at 21, one end of a fourth arm 22 disposed transversely toward the arm 17. 110

The transverse arms 20 and 22 are of similar lengths, and the opposed ends of these

arms are pivoted together, at 23. By forming the bracket 13 in this manner it will be triangular in shape when unfolded, as indicated in Fig. 2, and when the bracket is 5 folded, as shown in Fig. 3, its transverse arms 20 and 22 will be moved inwardly between the side arms 17 and 18.

Removably suspended from the bracket 10 by means of a suitable number of spaced 10 rings, as 24, movably guided on all of the arms 17, 18, 20, 22, is a bath sheet 25, the rings being arranged on these arms of the bracket before they are connected together. The sheet 25 may be of any desired material, 15 and this sheet is of a length whereby it will extend some distance below the top of the bath tub. The sheet 25 is preferably formed in a shape to correspond with the triangular bracket so that when in use it may be disposed 20 interiorly of the tub, in order to prevent water from flowing over the sides of the tub, and when the sheet is not in use it will be neatly folded simultaneously with the folding of the bracket 13, as explained, 25 after which the bracket may be swung on the post 10 so that the sheet 25 will be entirely clear of contact with the tub.

In order to permit persons of different heights to conveniently take a shower bath 30 or to allow the bather to shower parts of the body without wetting the hair if desired, on the post 10 under the foldable bracket 13 is provided an adjustable hollow water distributor 26. The water distributor 26 is 35 preferably of a pipe-like form of substantially a semi-circular shape whereby it will encircle part of the body of the bather when positioned between its arms, and the ends of this pipe-like distributor are closed. At 40 spaced intervals through the inner part of the periphery of the distributor are perforations 27, and leading into the interior of the distributor through an opening midway of the outer part of its periphery is a pipe 28. 45 The perforated pipe-like distributor is somewhat less in size than the triangular foldable bracket 13, and the pipe 28 is of a length so that the distributor will be moved on a vertical plane interiorly of the bracket 50 and the bath sheet 25 when the distributor is adjusted on the post 10. Serving as means for adjustably connecting the water distributor to the post 10, the end of the pipe 28 of the distributor proper is connected to a 55 chambered supporting sleeve, or casing, as 29.

The supporting casing 29 has an outer wall 30 and an inner tubular wall 31 of less diameter than the outer wall, and the upper and lower ends of the outer wall are 60 inturned and soldered or otherwise connected to the inner wall to provide an annular water-tight chamber 32 in the casing. Projecting from part of the outer wall 30 of the casing is an apertured boss 33 in 65 which is held the pipe 28 of the water dis-

tributer 26 so as to provide communication between the chamber 32 and the interior of the distributor through the medium of the passage through this pipe. Also extending from another part of the outer wall of the 70 casing 29 is a nipple 34, and the passage through this nipple communicates with the chamber of the casing for serving as an inlet to admit water therein for delivery through the pipe 28 and into the interior of 75 the distributor 26. The interior of the tubular wall 31 of the casing 29 is of a diameter to permit the casing to be guided over the post 10 so as to be movable thereon, and this inner wall as well as the outer wall 80 of the casing are connected by a tube, as 35. The passage through this tube 35 communicates with an opening in the tubular wall 31 and with an opening in the outer wall 30 of the casing, and the interior surface of 85 this tube is threaded for reception of a thumb screw 36 adapted to be rotated so as to engage and be disengaged with the post 10 for holding the casing 29 against movement when the water distributor is adjusted 90 at a suitable elevation.

In order to permit water to be delivered from the faucet 12 of the water supply system of the bath tub to the casing 29 and thence to the distributor 26, the faucet is connected to one end of a flexible tubular member, or pipe 37 having its other end connected to the nipple 34 of the chambered casing 29. The flexible pipe may be made of rubber, or any other suitable material, 100 and this pipe may be of a length to allow the water distributor 26 to be adjusted on the post 10 at a desired height either upwardly or downwardly. When a shower bath is taken by a person, the bracket 13 is 105 swung on the post 10 to a position over the open top of the bath tub, and by unfolding the bracket, as above described, the sheet 25 may be disposed so that its lower end portion will be interiorly of the tub. The distributor 26 is then adjusted to a desired height on the post 10 after loosening and tightening the thumb screw 36. By letting the water flow from the faucet of the bath tub it will pass through the flexible pipe 110 37, through the chamber 32 of the casing 29, through the pipe 28, into the distributor 26 from which the water will be delivered in the form of a shower through its perforations 27, and the bather may then allow 115 the shower of water to flow on any part of the body.

In the foregoing description, I have embodied the preferred form of my invention, but I do not wish to be understood as limiting myself thereto as I am aware that modifications may be made therein without departing from the principle, or sacrificing any of the advantages of this invention, therefore I reserve to myself the right to 120 125 130

make such changes as fairly fall within the scope of the appended claim.

Having thus described my invention, I claim as new and desire to secure by 5 Letters Patent:—

In a shower bath fixture for tubs, a stationary support adjacent to the tub, a substantially semi-circular hollow distributer of a pipe-like form having perforations on 10 its inner periphery, a water-tight supporting casing on the distributer, formed with an outer wall and an inner wall spaced from the outer wall to provide a chamber, the said casing having an inlet for reception of 15 water and having an outlet leading into the

interior of the distributer, and the inner wall of the casing being adjustably mounted on the support so that the distributer may be elevated to various heights over the open top of the tub, and a flexible tubular member leading from a source of water supply to the inlet of the casing for the delivery of water to the distributer whereby a person may take a shower bath. 20

This specification signed and witnessed 25 this thirty-first day of March, A. D. 1915.

JOSEPH ROSENBERG.
